UNITED STATES PATENT OFFICE

BURR N. MUNSON, OF MUNCIE, INDIANA

DESIGN FOR A SHIELD FOR VEHICLE WHEELS

Application filed March 19, 1931. Serial No. 39,165. Term of patent 7 years.

To all whom it may concern:

Be it known that I, BURR N. MUNSON, a citizen of the United States, residing at Muncie, in the county of Delaware and State of Indiana, have invented a new, original, and ornamental Design for Shield for Vehicle Wheels, of which the following is a specification.

Reference is had to the accompanying drawings forming a part hereof.

I claim:

The ornamental design for a shield for vehicle wheels substantially as shown.

BURR N. MUNSON.
